UNITED STATES PATENT OFFICE.

JAMES F. CRAVEN, OF CRAFTON, PENNSYLVANIA.

METHOD OF MAKING CHAINS.

1,242,324.

Specification of Letters Patent.

Patented Oct. 9, 1917.

Application filed April 5, 1915, Serial No. 19,224. Renewed August 22, 1917. Serial No. 187,701.

To all whom it may concern:

Be it known that I, JAMES F. CRAVEN, a resident of Crafton, in the county of Allegheny and State of Pennsylvania, have invented a new and useful Improvement in Methods of Making Chains, of which the following is a specification.

This invention relates to a method of making chains, and particularly forged or wrought metal chains made from a single solid bar and thereby dispensing with welding operations. In the manufacture of chains of this kind considerable difficulty is experienced in the final severance of the links from each other, due to the inaccessibility of the fin integrally connecting adjacent links, which not only is comparatively small but also is surrounded by the two links so that only very small and consequently light tools can reach it, it being also quite difficult to devise simple, effective and satisfactory automatic mechanism for operating upon this fin.

The object of the present invention is to provide a method which enables the fin integrally connecting adjacent links to be easily reached for manipulation by a tool to readily sever the links, which enables the use of a strong, serviceable tool for the severing operation, which can be carried out economically, satisfactorily and efficiently with simple and easily operated apparatus, which can be used for the production of forged metal chains of any weight and size, and which also subjects each link to a twisting or torsional action and thereby reinforces and strengthens the same, all with the final result of materially reducing the cost and improving the strength and qualities of chains of this kind, and also enabling chains to be made of metals which cannot be welded, such as copper, brass, aluminum, etc.

The invention comprises the several method steps hereinafter described and claimed.

In the drawings, Figure 1 is a diagrammatic view illustrating the formation of a chain by my method; Fig. 2 is a similar view, illustrating the manufacture of a series of integrally connected links which are subsequently severed to form the finished chain; Fig. 3 is a cross sectional view, on a larger scale, on the line 3—3, Fig. 2; Fig. 4 is a cross section on the line 4—4, Fig. 2; Fig. 5 is a perspective view of the trimming

dies; and Fig. 6 is a similar view of the link severing devices.

Briefly stated, this method consists in first forming from suitable bar stock a series of integrally connected partially formed chain links, then shifting the relative positions of each two successive links to expose the metal fin integrally connecting said links, and then severing the links by suitable manipulation of said fin. The method can be carried out either by hand or by suitable automatic mechanism, which may consist of common and well known machines adapted for this particular method.

In carrying out the method by hand, let us assume that the operator is supplied with a series of integrally connected chain links formed from a solid bar in any of the well known ways, such an integral link bar being represented by the successive links marked 5, 6, 7 and 8 in Fig. 1. These links are interlocked with each other, are substantially completely formed or shaped, and successive links are integrally connected to each other where they interlock by small fins or walls, one of which is indicated by the fine dotted lines at 20, Fig. 1. This fin can ordinarily be reached only by a tool applied at an angle of 45 degrees to the planes of the two links 7 and 8. It is confined or inclosed by said links so that it is not wholly exposed and can only be reached by a fine delicate tool and cannot be efficiently operated upon with the links in the positions shown for severing them from each other.

In carrying out my method each two successive or adjacent links are shifted relatively to each other to expose said fin to sever the links. This can be done in various ways, such as by shifting the position of either link while holding the other stationary, or by moving both links. The link 8 is connected to those links which have already been severed from each other by previous operations and can be more readily manipulated than the link 7, which is fastened to the end portion of the bar. Consequently I prefer to hold the link 7 stationary and move the link 8, which is bent or rotated laterally around an axis perpendicular to the plane of the link 7 and passing through the end portion of the link 8 at the point marked A in Fig. 1. Link 8 is swung around through a suitable angle, which usually is 90 degrees or more, being shown as turned from the position in dotted

lines to that in full lines, Fig. 1. In this position the fin 20 connecting links 7 and 8 is exposed so that it can be reached by a tool for severing the links. This tool may be of 5 any suitable form, either a punch for completely removing the fin 20, or merely a nicking tool for severing the links by a cutting or pinching action without removing any metal.

10 When the link 8 is rotated, as described, the fin 20 connecting it to link 7 prevents the end portion of said link from turning, so that it is subjected to a twisting or torsional action, which not only affects that 15 portion of the link directly connected to the link 7, but also extends around the body portion of the link, the effect dying away with the distance from the fin 20. It is well known that when metal is subjected to a 20 torsional action sufficient to produce a permanent set therein its ability to resist bending and tensile strains is increased. Consequently the strength of each link is increased by rotating it to expose the fin 20, 25 the effect being most pronounced at the points where two links are integrally connected. Moreover, by severing said links without removing the metal of the fin 20 this fin can subsequently be worked into the 30 bodies of the links to additionally reinforce them against tensile and other strains.

The series of integrally connected links can be formed in any suitable manner. For example, a rolled bar 25 of cruciform cross 35 section and having two webs 26 in planes at right angles to each other may be subjected to the action of notching dies or cutters which act successively upon the two webs 26 to remove small, substantially triangular 40 portions of the metal, as indicated at the shaded portions marked 27, Fig. 2, and subsequently subjected to the action of punching dies 28 whose cutting portions, in cross section, are of the shape shown in Fig. 5. 45 These punching dies will act successively upon the two webs 26 of the bar and remove the central portions of the links, which are shown shaded at 29. The notching dies and punches can be carried by a common movable 50 punching head past which the bar 25 is fed step by step, being turned back and forth through an angle of 90 degrees so that the cutters or punches will act successively upon its two webs. This leaves the bar in the 55 form of a series of partially formed chain links 30, as in Fig. 2, connected by the integral fins 20 shown in Fig. 1, which can be exposed for severing the links from each other, as before described. The links are 60 subsequently worked up into finished form in any suitable manner.

If desired, the metal can be worked up into the form of a series of integrally connected partially formed links from a solid 65 bar without materially removing metal

therefrom by forging or working either wholly or partially the triangular portions 27 and the central portions 29 of the links into the links themselves. One way of doing this is by passing a solid bar of suitable 70 cross section through rolls having operating faces formed to simultaneously work the bar into the cruciform cross section, form the triangular notches 27 between adjacent links and either wholly open out the central portions of said links by working the metal into the links themselves, or partially by thinning down the shaded portions 29 to a thin film or web, as shown in Fig. 4. These operations 75 can be most conveniently and satisfactorily carried out if the partially formed links are of circular form, which increases the area of the central open portion of said links and enables the subsequent use of substantially circular punches of maximum size and 80 strength for removing the central webs or film. In Fig. 1 the integrally connected links 1 to 8 inclusive have been formed in the manner just described, each link having a central thin web or film 29 and an outer 85 circular body portion 31 which is substantially circular in radial cross section, similarly to the link shown in Fig. 4. These integrally connected links are advanced step by step through a suitable machine, being alternately turned back and forth through 90 angles of 90 degrees between successive operations. At the position represented by the link 3 the central thin webs or films 29 are removed by punching tools of the form 95 shown in Fig. 5, leaving said links connected by the fins 20. As each link reaches the position of the link 8 it is bent or rotated 100 to one side and severed by a tool carried by the same head which carries the trimming die 28 and co-operating with a similar stationary tool. This tool may be of the form shown in Fig. 6, having a knife-like side portion 32 for pinching off the fin 20 from the link 7 and a concave portion 33 for 105 shaping up said link. The severed or separated round links finally reach the position of the link 12 in Fig. 1, where they are subjected to the action of suitable shaping tools or dies for flattening them into the oval 110 form of the link shown at 13, which is the usual form of chain links. At any suitable point in the machine each link may be subjected to the action of a suitable forging or 115 shaping tool for working the metal of the fin 20 into the link and smoothing up the otherwise rough surfaces.

The operations are carried out with the metal at a fairly good heat, say a little more than a cherry red, so that each link can be 120 twisted without straining its fibers or impairing its strength, but on the contrary reinforcing it by the twisting action as described.

This method enables chains to be made 125 economically and at a high rate of speed on 130

simple automatic mechanism, and also materially lowers the cost and increases the strength and other qualities of the chains.

What I claim is:—

5 1. A method of separating integrally connected links formed from a solid bar, consisting in shifting two successive links relatively to each other around an axis transverse to the bar to expose the connecting fin, and then severing said links.

10 2. A method of separating integrally connected links formed from a solid bar, consisting in bending one link to an angular position relatively to the adjacent link without changing the position of the connecting fin to thereby expose said fin, and then severing the links.

15 3. The method of separating integrally connected links formed from a solid bar, consisting in bending one link to an angular position relatively to the adjacent link to expose the connecting fin and simultaneously

twisting the metal of one link to reinforce the same, and severing said links.

4. The method of separating integrally 25 connected links formed from a solid bar, consisting in rotating one link about a transverse axis lying in the plane of the link and passing through its end portion and thereby exposing the connecting fin, and then severing 30 said links.

5. The method of separating integrally connected links formed from a solid bar, consisting in rotating one link about a transverse axis through its end portion and thereby exposing the connecting fin and simultaneously 35 twisting the rotated link, and then severing said links.

In testimony whereof, I have hereunto set my hand.

JAMES F. CRAVEN.
